UNITED STATES PATENT OFFICE.

JOHN P. REINECKE, OF PITTSBURG, PENNSYLVANIA.

SAFETY APPARATUS FOR OIL-TANKS.

SPECIFICATION forming part of Letters Patent No. 291,085, dated January 1, 1884.

Application filed November 22, 1883. (No model.)

To all whom it may concern:

Be it known that I, JOHN P. REINECKE, of Pittsburgh, in the county of Allegheny and State of Pennsylvania, have invented a new and useful Improvement in Safety Apparatus for Oil-Tanks; and I do hereby declare the following to be a full, clear, and exact description thereof.

My invention relates to an improvement in apparatus for removing inflammable gases from oil-tanks; and it consists in devices which cause an induced current of air to pass into the tank above the surface of the oil, and at the same time conduct the displaced gases to a point where they may be used as fuel or discharged with safety into the atmosphere.

I will now describe my invention, so that others skilled in the art may manufacture and use the same, reference being had to the accompanying drawing, forming part of this specification, which is a vertical section through the tank, showing my improved apparatus.

It is well known that the gases developed or evolved from the oil in oil-tanks are often of two classes—viz., those which are heavier than the air and those which are lighter. Therefore, in applying my invention, the flow of the gases may be rendered automatic in two ways—in case of the lighter gases, by a draft such as can be produced by a stack or other means, and displacement, and in the case of the heavier gases, either in a like manner by a draft and displacement or by siphonic action and displacement.

The essential features of my improved apparatus are an inlet for the air, arranged so as to deliver the air at the desired point in the tank, (either at the surface of the oil, beneath the gases, or at the top of the tank, above the gases, according as to whether the specific gravity of the gases is less or greater than the specific gravity of the air,) an outlet and conduit for the gases, arranged either at the surface of the oil or at the top of the tank, and a discharge-orifice in the conduit, preferably situated at a point distant from the tank, and arranged on such a level with relation to the gas in the tank as to produce a draft or siphonic action.

In the drawing, *a* represents the tank, in the lower part of which is the oil *b*. On the sur-

face of the oil are the floats *c*, which support the telescopically-jointed tubes *d*. These tubes *d* extend from the floats *c* into stacks *e*, arranged on the cover or roof of the tank, and they are attached to the floats in such a manner as to leave an opening for the passage of the air from the tubes into the tank at the surface of the oil. The tubes *d* and stacks *e* are also united by a telescopic joint. The stacks *e* are open at their upper ends, which are protected by the hoods *f*.

In the stacks *e*, between the roof of the tank and the top of the stacks, are valves *g*.

Extending from the upper portion of the tank *a* to a point below the level of the ground, and thence to a point distant from the tank, is a gas outlet and conduit pipe, *i*, which is open at its upper end. The other end of the pipe *i* opens into a valve-chamber, *k*, in which is a hinged gate, *m*, which prevents the backward flow of the gases through the pipe *i*; and communicating with the chamber *k* is a vertical stack, *n*, which extends above the level of the tank. This stack should extend to a point sufficiently high above the tank to produce a draft through the pipe *i*.

On the roof of the tank *a* is a gas-chamber or casing, *o*, from which a telescopically-jointed tube, *p*, extends downward to a float, *q*, on the surface of the oil, which tube and float are similar to the floats *c* and tubes *d*. This casing *o* communicates with the pipes *i* by a pipe, *r*, outside of the tank, and in the pipe *i*, between the tank and the pipe *r*, is a valve, *s*. A valve, *t*, is placed in the pipe *r*, just above the intersecting point of the two pipes *r* and *i*, and an outlet or discharge pipe, *u*, leads from the pipe *r*, just above the valve *t*. An air-inlet pipe, *w*, extends from a pump, *v*, to and into the top of the tank, and in the pipe, at the level of the top of the tank, is an inlet-opening, *x*, which may be closed by the valve *x'*.

The operation is as follows: In order to remove the lighter gases from the upper portion of the tank, the inlet-pipe *w* and the outlet-pipe *r* are closed by means of the cocks or valves *w'*, *t*, and *u'*. The air passes through the open ends of the stacks *e* down through the tubes *d* and into the tank at the surface of the oil. At the same time the lighter gases in the tank pass through the pipe *i* into and

through the stack *n*, the induction of the air and the displacement of the gases being caused by the draft from the stack.

In order to remove the heavier gases from the tank, the stacks *e* are closed by the valves *g* and the pipe *i* by the valve *s*, and the valves in the pipes *w* and *u* are opened. The air passes through the inlet *x* into the upper portion of the tank, and the heavier gases pass through the tube *p*, casing *q'*, and pipe *r* into the discharge-pipe *u*, the induction of the air and displacement of the gases being caused by siphonic action. By shutting the valve *u'* in the pipe *u* and opening the valve *t*, the heavier gases may also be removed from the tank by the draft through the stack *n*.

The air-pump *w* may be used to start the siphonic flow of the gases, or to aid in the displacement of the gas through either or both of the gas-outlet devices.

The gas, as it is discharged from the pipe *u*, may be used as fuel or for illuminating purposes.

The advantages of my invention are that the inflammable gases are drawn away from the tank, and the danger of fire from the igniting of the same, either by lightning or from other causes, is greatly lessened. I do not herein claim the method of preventing the accumulation of inflammable gases

in oil-tanks, as the same forms the subject-matter of a prior application filed August 3, 1883, Serial No. 102,669.

Having thus described my invention, what I claim, and desire to secure by Letters Patent, is—

1. The combination, with an oil-tank, of an air-induction pipe and a gas-eduction pipe, said pipes arranged with their open ends on different horizontal planes within the tank, substantially as and for the purpose specified.

2. The combination, with an oil-tank, of an air-induction pipe and a gas-eduction pipe, said pipes arranged with their open ends on different horizontal planes within the tank, one of said pipes being provided with a float, so as to be automatically adjustable, substantially as and for the purpose specified.

3. The combination, with an oil-tank, of an air-induction pipe, a gas-eduction pipe, and a pump for creating a draft through the tank above the surface of the oil, substantially as specified.

In testimony whereof I have hereunto set my hand this 17th day of November, A. D. 1883.

JOHN P. REINECKE.
